UNITED STATES PATENT OFFICE.

SWAN J. LEVEEN AND EDWARD A. MARTIN, OF ROCK ISLAND, ILLINOIS, ASSIGNEES,
BY MESNE ASSIGNMENTS, TO TRIO MANUFACTURING COMPANY, A CORPORATION
OF ILLINOIS.

SAFETY-FUSE.

975,261.

Specification of Letters Patent.

Patented Nov. 8, 1910.

Application filed December 4, 1907. Serial No. 405,063.

To all whom it may concern:

Be it known that we, SWAN J. LEVEEN and EDWARD A. MARTIN, citizens of the United States, residing at Rock Island, county of Rock Island, State of Illinois, have made a certain new and useful Invention in Safety-Fuses, of which the following is a specification.

The invention relates to safety fuses, and particularly to the type of fuses known as inclosed safety fuses.

The object of the invention is to provide a safety fuse of simple construction, economical to manufacture, and which is efficient in use.

A further object is to provide a safety fuse, of the character referred to, having few and simple parts, which may be readily and quickly assembled, whereby renewals of the fusing portions may be readily and quickly effected.

A further object is to provide means which are simple and efficient for revealing, on inspection, whether or not the fuse is intact or has been blown or tampered with.

A further object is to provide means for revealing on inspection of the device the amperage or other desired rating of the fuse.

Other objects of the invention will appear more fully hereinafter.

The invention consists substantially in the construction, combination, location, and relative arrangement of parts, all as will be more fully hereinafter set forth, as shown in the accompanying drawings and finally pointed out in the appended claims.

Referring to the accompanying drawings and to the various views and reference signs appearing thereon, Figure 1 is a view in side elevation of one form of safety fuse embodying our invention, all the parts being assembled and the device ready for use. Fig. 2 is a view in longitudinal section of the same. Fig. 3 is a broken view in longitudinal section, of the end of the casing, showing means for securing the fuse strip therein. Fig. 4 is a similar view of the end cap or ferrule, showing the manner of mounting the terminal contact plates. Fig. 5 is a detached view of the fuse strip. Fig. 6 is a view similar to Fig. 1, showing a modified form of fuse embodying the principles of our invention. Fig. 7 is a view in longitudinal section of the construction shown in Fig. 6. Fig. 8 is a broken view in

longitudinal section of the end of the fuse case shown in Fig. 6. Fig. 9 is a similar view of the end cap or ferrule employed in connection with the form of fuse shown in Fig. 6 and showing the manner of mounting the terminal contact plates. Fig. 10 is a view similar to Fig. 5, showing a slightly modified form of fuse strip. Figs. 11 and 12 are views in longitudinal section of the fuses respectively shown in Figs. 1 and 6, the plane of section being at right angles to the plane of section of Figs. 2 and 7.

The same part is designated by the same reference sign wherever it occurs throughout the several views.

In the construction of fuses, and particularly fuses of the inclosed type it is desirable that the various parts thereof be simple in construction, and capable of being readily and easily assembled, and that the fusing part, when blown, may be readily and easily replaced, that means be provided which are reliable and positive in operation for readily revealing on inspection whether or not the fuse has been blown, and that means be provided to enable the rating or capacity of the fuse to be revealed on inspection.

It is among the special purposes of our present invention to provide a fuse which embodies these various desirable features.

In carrying out our invention we employ a casing A of suitable insulating, and preferably fire proof material, adapted to receive and contain the fuse strip H, therein. This fuse strip may be of any suitable or convenient material, such, for instance as zinc, adapted to fuse or burn out under the current conditions to which it is designed. In practice we prefer to employ a flat strip, as shown, having a portion intermediate its ends, of reduced width, as indicated at M. This fuse strip is inserted and inclosed longitudinally within the case, and is surrounded with a suitable powder or other composition K, in the usual manner, the function of which is to absorb the gas and smother the arc when the fuse blows. Caps I, are secured in the ends of the case and serve to close such ends, said caps having slits or openings therethrough through which the ends of the fuse strip extend, as clearly shown in the drawings. The caps I may be secured in the ends of the case in any suitable or desirable manner. We have shown a simple arrangement wherein the caps are

provided with annular flanges R, which bear against the end surfaces of the casing, and we provide the fuse strip H with tongues J, stamped out of the body thereof and which are arranged to engage against the outer face of the caps, as clearly shown, thereby not only holding the caps in place, but also securing the fuse strip in place. These tongues J, may be formed midway the transverse width of the fuse strip, as shown in Fig. 5 or they may be formed in the edges thereof as indicated in Fig. 10. It will be readily seen that the tongue at one end of the strip engages and bears against the outer surface of the cap at that end of the case while the tongue at the other end of the strip engages and bears against the outer surface of the cap at the other end of the case, that is, the surface which presents in a direction opposite to that in which the outer surface of the other cap presents, and consequently the caps and also the strip, are thus easily assembled and efficiently secured to the case.

The ends of the fuse strip extend beyond the caps I, and these extending ends form the circuit terminals of the fuse. In order to form efficient bearing contact for these projecting ends with the line terminals, we arrange said ends to be received between contact blades or plates. These may be arranged for use in connection with knife clip line terminals, as indicated at D, Figs. 1, 2, 4 and 11, or in the ferrule type of fuses, as indicated at D', in Figs. 7 and 9.

The blades or plates D, D', are shown of angle form, but our invention is not to be limited or restricted in this respect. In the case of the knife-clip type the angle portions of these blades or plates are secured by means of rivets G, or other suitable devices on the inner surface of cups or ferrules C, which are designed to slip over or upon the ends of the cases and which may be held thereon by friction or otherwise, and which not only serve to carry the contact blades or plates but also to give a finished appearance to the fuse. The ends of the contact blades or plates extend through a slot or opening in the cup or ferrule, and outside of the case, and the projecting ends of the fuse strip are received therebetween as clearly shown. If desired, and in order to enable the contact blades or plates to readily adjust themselves to their bearing contact against the end of the fuse strip, the securing rivets G, may be arranged to pass through elongated slots L, in the ferrules, as shown in Fig. 4, thereby permitting slight movement of the blades or plates in adjusting themselves to efficient contact with the ends of the strip.

In the case of the ferrule type instead of the contact blades or plates D', extending through the cups or ferrules C', said plates

or blades extend inwardly, as clearly shown in Figs. 7 and 9, and receive the end of the fuse strip therebetween.

In order to reveal on inspection whether or not the fuse has been blown we provide a very simple and efficient indicator which, in the particular form illustrated in the drawings, but to which our invention is not to be limited or restricted, comprises a wire F, preferably of small cross sectional area, connected up in shunt to the fuse strip. In practice we prefer to arrange this wire on the outside of the case A, but in this respect we do not desire to be limited. This wire is formed into a loop at P, into which is engaged the hooked end of a spring indicator E. This indicator is suitably secured at one end as, for instance, to the case and when the hooked end thereof is not engaged in the loop P, said spring stands out away from the case, but when the hooked end thereof engages in the loop said spring is held down against the side of the case. It will be seen that this arrangement provides a most efficient, simple and positive indicator for revealing on inspection whether or not the fuse has been blown.

The rating or capacity of the fuse may be revealed in many different ways. In Figs. 1 and 6, we have shown labels B, adapted to be applied to the case and on which the information regarding the rating or current capacity of the fuse, as well as other information or directions may be printed. This label may be applied over the indicator wire thereby affording means for protecting such wire. In this case the label is provided with a hole through which the loop P, of the wire extends.

If desired the rating and current capacity of the fuse may be indicated in other ways. We have shown a simple and efficient way for accomplishing this result wherein we extend the ends of the fuse strip beyond the ends of the plates or blades D, see Figs. 1, 2 and 4. In this case the strip may have stamped or otherwise placed on such projecting end the desired information as to its rating or current capacity.

From the foregoing description it will be seen that we provide an exceedingly simple and efficient fuse which can be economically manufactured, and readily and easily assembled, and of such structure that when it is blown the most expensive parts, namely, the ferrules and contact plates are saved thereby enabling the fusible part to be readily renewed. It will also be seen that on inspection it may be revealed at once whether or not the fuse is blown, and also the rating or current capacity of the fuse.

Having now set forth the object and nature of our invention and various constructions embodying the principles thereof, what we claim as new and useful and our

own invention and desire to secure by Letters Patent is:—

1. In a safety fuse, a case, a fuse element arranged therein, engaging means between the case and fuse element for locking these parts together, said fuse element having its ends extending beyond the ends of the case, and cups removably mounted on the ends of the case and carrying outwardly extending contact plates arranged to receive therebetween and to contact with the extending ends of the fuse element.
2. In a safety fuse, a case, a fuse element arranged therein engaging means between the case and fuse element for locking these parts together, having its ends extending beyond the case, a cup removably mounted on each end of the case, and outwardly extending contact plates carried by said cups to receive therebetween the projecting ends of the fuse element, said contact plates being independently and loosely mounted for relative movement whereby they adjust themselves to the fuse element ends.
3. In a safety fuse, a case, a fuse element arranged therein and having its ends extending beyond the ends of the case, cups for the ends of the case, and self adjusting contact plates independently mounted on said cups, and arranged to receive therebetween the projecting ends of the fuse strip.
4. In a fuse, a case, a fusible strip arranged therein engaging means between the case and fuse strip for locking these parts together, said fuse strip having its ends extended beyond the ends of the case and removable cups for the ends of the case, said cups carrying outwardly extending loosely mounted contact plates to receive the extending ends of the fusible strip therebetween, and means for clamping said plates together whereby said contact plates are self adjusting to bearing contact against said ends.
5. In a fuse, a case, a continuous strip extending through the case, and independently and loosely mounted contact plates arranged at the ends of the case to receive the ends of the strip therebetween.
6. In a fuse, a case, a continuous fuse strip extending through said case, means for locking the same therein, and independently and loosely mounted contact plates, arranged in pairs and carried by the ends of the case to receive therebetween the ends of said strip.
7. In a fuse, a case, a continuous fuse strip extending through said case and self adjusting contact plates to receive the ends of said strip.
8. In a fuse, a case having caps at the ends thereof and a fuse strip extending

through the case and beyond the caps and engaging the caps on the outer end surfaces thereof, and in opposite directions whereby the parts are held together.

65

9. In a fuse, a case having caps at the ends thereof, and a fuse strip extending through the case and beyond the caps and having tongues to engage against the outer surfaces of the caps.

70

10. In a fuse, a case having caps in the ends thereof, a fuse strip extending through the case and caps, and self-adjusting contact plates to engage the extending ends of the strip.

75

11. In a fuse, a case having caps in the ends thereof, a fuse strip extending through the case and caps, and having means to engage the caps to lock the parts rigidly together, and contact means to engage the ends of the strip.

80

12. In a fuse, a case having flanged caps in the ends thereof, the flanges of the caps bearing against the end surfaces of the case, and a fuse strip extending through the case and caps and having means to engage the outer surfaces of the caps at the respective ends of the case, and in opposite directions to hold the parts together.

85

13. In a fuse, a case having closed ends, a fuse strip extending through said case and having the ends thereof projecting beyond the closed ends of the case, and self adjusting contact means to engage the projecting ends of the strip.

90

14. In a fuse, a case having closed ends, a fuse strip extending through said case, and projecting beyond the closed ends thereof, cups carried by the case at its ends and provided with relatively movable clamping contact plates independently mounted and adapted to receive therebetween and contact with the projecting ends of the strip.

95

15. In a fuse, a case having closed ends, a fuse strip extending through said case and the closed ends thereof, said fuse strip having a portion intermediate its ends of reduced width, and independently and loosely mounted self adjusting contact plates arranged at the closed ends of the case to receive therebetween the extending ends of the fuse strip.

100

In testimony whereof we have hereunto set our hands in the presence of the subscribing witnesses, on this 26th day of November A. D., 1907.
